MULTIPLE LENS CAMERA

Samuel Kitrosser, Lexington, and Frederick W. Macone,
Carlisle, Mass., assignors to Avant Incorporated, Lin-
coln, Mass., a corporation of Massachusetts

Filed Oct. 30, 1963, Ser. No. 77,210

Term of patent 14 years

(Cl. D61—1)

FIG. 1

FIG. 2

FIG. 3

FIG. 1 is a perspective view of a multiple lens camera showing our new design;

FIG. 2 is a top plan view thereof;

FIG. 3 is a bottom plan view thereof.

The essential features of our design are shown in full lines.

We claim:

The ornamental design for a multiple lens camera, as shown and described.
